APPARATUS FOR SUBSURFACE SURVEYING

David G. Hawthorn, Tulsa, Okla., assignor to
Geophysical Research Corporation, New York,
N. Y., a corporation of New Jersey

Application January 14, 1936, Serial No. 59,096

3 Claims. (Cl. 255—28)

This invention relates to apparatus for sub-surface surveying.

In a recently developed method of exploring sub-surface formations, the drill bit of a standard 5 boring machine is used as an electrode for passing electricity into the earth at the bottom of a bore hole in order to test the electrical resistance of the formation in which the bit is operating to determine the nature of such formation. An object of this invention is a drill stem incorporating 10 an insulated conductor designed to carry electricity to the drill bit.

A drill stem embodying the invention consists as usual of a number of lengths of pipe joined 15 end to end by the usual male and female connectors at the ends of the lengths of pipe. In each connector is an insulated electrical contact which is adapted to be engaged by a contact in a connector of the opposite type upon union of 20 said connectors. A small conduit is fixed to the inner periphery of the pipe and through it passes an insulated electrical conductor having its ends connected to said contacts. A drill collar which is electrically insulated internally and externally, 25 is interposed between the bottom connector of the drill stem and the drill bit thus allowing the bit to function as an electrode and is provided with an electrical contact to engage the electrical contact in said bottom connector. With this 30 arrangement, the connecting together of the several lengths of pipe in the usual manner automatically builds up an insulated electrical path from the top of the drill stem to the drill bit. The normal procedure in increasing the length of 35 the drill stem as the depth of the bore increases or in removing the drill stem for replacement of the bit is in no way interfered with by the arrangement for conducting electricity to the drill bit.

40 Other objects, novel features and advantages of this invention will become apparent from the following specification and accompanying drawings, wherein:

Fig. 1 is a diagrammatic view of a drill stem 45 embodying the invention;

Fig. 2 is an elevation of one section of the drill stem connected at either end to other sections;

Fig. 3 is a longitudinal section through the bit 50 and collar by which it is connected to the drill stem;

Fig. 4 is a longitudinal view of a male and female connector in position to be coupled;

Fig. 5 is a similar view with the connectors 55 coupled;

Fig. 6 is a transverse section on the line 6—6 of Fig. 5;

Fig. 7 is an enlarged fragmentary view of the contacts in the male and female connectors in position about to be engaged;

Fig. 8 is a view similar to Fig. 7 with the contacts in engagement, and

Fig. 9 is an elevation of the female connector contact.

As shown in Fig. 1, the drill stem consists of a 10 series of pipe lengths 10 jointed together by couplers or tool joints 11 with a drill collar 12 attached to the bottom length and being in turn attached to the drill bit 13. Each coupler 11 consists of a male connector 14 and a female connector 15 which are permanently secured to the pipe lengths 10 and which are provided with co-operating tapered screw-threaded portions by engagement of which the two connectors are joined to form a coupler 11, such coupler construction being of the standard type now in general use and known as a tool joint.

15 In the bore of the male connector is provided a contact 16 and in the bore of the female connector is provided a contact 17. The contact 16 comprises a metal ring enclosed with insulation such as rubber except along its upper edge. The insulation covered contact is mounted in a split sleeve 18 which rests against a shoulder in the connector bore and has a force fit in said bore. The contact 17 consists of a metal helix terminating at each end in an annulus, the contact being completely enclosed with insulation such as 20 rubber except along its bottom edge. The upper end of the insulation covered contact 17 is 25 mounted in a split sleeve 19 which bears against a shoulder in the connector bore and has a force fit therein. The insulation on the connector 16 extends beyond the uncovered edge of the contact to form an annular channel. The insulation 30 on the contact 17 tapers at the lower edge thereof to form a wedge which is received in the channel at the upper edge of the contact 16. The taper of the walls of the channel is less than the taper of the wedge so that the walls of the channel 35 are spread upon engagement of the wedge in the channel to insure effective insulation of the contacts 16 and 17 along the meeting edges thereof. A conduit 20 extends longitudinally of each 40 length of pipe 10 and is brazed or otherwise connected permanently to the inner periphery of the pipe. An insulated electrical conductor 25 extends through the conduit 20 and is electrically connected at one end to contact 16 and at the 45 opposite end to a contact 17. The space between 50

55

the conductor 21 and the inner wall of the conduit 20 may be filled with any suitable plastic material to hold the conductor firmly in place.

The drill bit 13 is of standard construction and is provided with a screw-threaded boss 22 which projects into the screw-threaded box at the lower end of the drill collar 12. The bore of the drill collar is provided with a liner 23 of insulating material and is surrounded by a sleeve 24 of insulating material such, for example, as bakelite. The upper end of the sleeve 24 is screw-threaded and extends into the screw-threaded box of a connector 14a which is provided with a contact 16 from which an insulated conductor 21a leads to the upper end of the drill collar 12. A ring 25 of insulating material is interposed between the upper end of the drill collar 12 and a shoulder in the bore of the connector 14a. The surface of the drill collar is roughened in any suitable manner, such as knurling, to prevent slippage of the sleeve 24 on the drill collar.

In a drill stem made in accordance with the invention, the usual mixture of mud and water is forced through the central bore and out the discharge ducts 13a in the bit in the usual manner, the cylindrical shape of the contacts 16 and 17 and their supporting members permitting free flow of such liquid. The top length of pipe 10 is connected in the usual manner to the standard Kelly joint 28 which is associated in the usual manner with a rotating drive wheel 29. The Kelly joint 28 is provided with a suitable electrical contact (not shown) which engages the top connector 16 and is connected by any suitable collector ring and brush arrangement with the positive terminal of a battery B through an ammeter or ohm meter M, the negative terminal of the battery being grounded. Electrical energy is thus supplied to the drill bit and the major part of the electrical current is discharged from the bit into the sub-surface formation at the bit blade as the best contact is at this point. The bit thus acts as a dissipating electrode and from readings observed on the ammeter or ohm meter, variations in the resistance of the sub-surface formation may be determined, thereby giving indication of the character of the formation.

As the bore increases in depth, additional sections may be added to the drill stem in the usual manner merely by disconnecting the Kelly joint from the top length of pipe, inserting the additional section and connecting the Kelly joint to the top end of the added section. The drill stem may be drawn up and disconnected in the usual

manner for the purpose of replacing the bit and without any precaution having to be taken with respect to the electrical connections.

In joining together the male and female connectors at the ends of two sections of pipe, it is necessary only to project the male section into the female section until the threads engage and then effect slight relative rotation thereof to couple the connectors firmly together. The exposed edges of the contacts 16 and 17 will be brought into engagement at about the same time that the threads of the connectors engage each other and in the final coupling together of the connectors the edges will be in sliding contact as the connectors are rotated into tight coupling engagement. The contact 17 is sufficiently resilient to be slightly compressed during the coupling operation while exerting sufficient pressure to insure good electrical conductive engagement between the edges of the contacts. The overall insulation of the contacts prevents any leakage of electrical energy, thus insuring a highly conductive electrical path from the top to the bottom of the drill stem.

I claim:

1. A drill stem section comprising a length of pipe, a conduit fixed to the inner periphery thereof, male and female threaded connectors at opposite ends of said pipe, a metal annulus rigidly supported in one connector, a metallic helical member supported in the other connector and terminating in a second annulus, said first annulus and said helical member being coated with electrical insulation except for an edge of each annulus, the annulus of each connector being effective to be engaged by an annulus in a connector of the opposite type upon union of said connectors, and an insulated electrical conductor passing through said conduit and having its ends connected to said contacts. 40

2. A drill stem section according to claim 1 in which the insulation for one annulus extends beyond the exposed edge thereof to form a tapered trough and the insulation for the other annulus tapers to the exposed edge thereof to form a 45 wedge.

3. A drill stem section according to claim 1 in which the insulation for one annulus extends beyond the exposed edge thereof to form a tapered trough and the insulation for the other annulus tapers to the exposed edge thereof to form a wedge, the taper of the trough being different than the taper of the wedge.

DAVID G. HAWTHORN.
